BRANDING MACHINE

Elmer Litchfield, Oakville, Ontario, Canada, assignor to The Oakville Basket Company Limited, Oakville, Ontario, Canada

Application February 21, 1938, Serial No. 191,700

6 Claims. (Cl. 101—8)

This invention relates to apparatus for branding candy sticks and similar small sticks with the name or trade mark of a manufacturer, or other markings. Such sticks are usually quite thin in diameter being as small as $\frac{5}{32}$ " or $\frac{1}{16}$ ". With sticks of such small diameter, it is very difficult with machines at present in use to apply a brand of any size, and the chief object of the present invention is to devise a branding machine capable of applying a brand to a larger portion of the circumference of the stick thus enabling the application of a larger brand or marking to the stick.

Further objects are to devise a machine capable of handling sticks of different lengths, having improved feeding means, improved means for maintaining clean the branding part of the machine and having improved delivery means.

I attain my objects by providing a hopper for receiving the sticks, said hopper being adjustable in width and provided with means for agitating the sticks in the delivery end of the hopper; by providing a stick carrying wheel for carrying the sticks from the hopper past the branding mechanism, by providing means for causing a rotation of said sticks on said wheel while the sticks are being subjected to the branding operation and by providing means for stripping the sticks from the carrier wheel after branding has been completed.

The apparatus is hereinafter more specifically described and illustrated in the accompanying specifications and drawings in which

Fig. 1 is a side elevation, partly broken away, of the machine;

Fig. 2 a plan view of the same;

Fig. 3 a front view of the branding means with the stick carrying drum, the latter being broken away;

Fig. 4 a plan view illustrating the method of mounting the branding means in its support; and

Fig. 5 a vertical section of the same.

In the drawings like numerals of reference indicate corresponding parts in the different figures.

1 indicates a frame suitably shaped for supporting the various parts. At one end of the frame is mounted a hopper, having an inclined bottom leading to an inclined stick guide 3. The hopper is formed with two side members 2 having inwardly and outwardly directed flanges 42, at their lower edge, the inturned flanges supporting the ends of the sticks. These side members are slidably mounted on cross bars 43, on the frame 1, to permit of adjusting their spacing to suit sticks of different lengths. Set screws 44, are

provided to lock the side members as adjusted.

The central part of the delivery end of the hopper 2, is open above the guide 3, and in this opening operates the agitator 4, pivoted on the frame. This agitator has an outwardly bent portion 5, which overlies sticks as they pass to the guide 3, and also has bent upwardly therefrom a dog 6, which is positioned to be engaged by a ratchet 7, on a shaft 8, journaled in the frame and driven by chain and gears 10, from the main drive shaft 11, of the machine. It will be seen that as the ratchet is revolved the lower end of the agitator is moved back and forth to agitate the sticks on the lower part of the hopper and ensure the regular feeding thereof to the stick guide 3.

The sticks are fed from the stick guide to the rotary stick carrier 12, the face of which is provided with transverse grooves 13, of a depth and width to receive a single stick. This rotary stick carrier is driven by means of chain and gears 14, from the main drive shaft 11.

This rotary stick carrier carries the sticks one by one beneath the branding means, which will be hereinafter described.

After leaving the branding means, the sticks are carried by the rotary stick carrier to the stripper fingers 15, which extend into circumferential grooves 16, in the rotary stick carrier, and cause the branded sticks to pass into the receiving tray 17, supported on the frame 1.

On a support 18, fulcrumed on the frame 1, is carried the brander 19, which is preferably of the electric-heated type, 28 being the lead wires for the heating element. In Fig. 1 the brander 19, and its support 18, are shown in operative position in full lines and in inoperative position in dotted lines.

Extending upwardly from the lower part of the frame 1, is a support 21, on which is pivoted an arm 22, for holding the brander support 18, in raised position. This arm 22, has a pin 23 projecting from its side and adapted, when the arm 22, is in the position shown in dotted lines in Fig. 1, to hold the brander support 18, in partly raised position. This arm 22, is provided with a notch 24, adjacent its upper end to receive a pin 25, on the brander frame 18, to hold the latter in fully raised position. The frame 18, is provided with a handle 26, to facilitate its being lifted to its upper position.

The brander 19, comprises a housing at the lower end of which is supported the branding element 19b, which is heated by a heating element within the housing. This housing 19a, is

adjustably mounted relative to the frame 18, to permit of its being rocked longitudinally or transversely of said frame to position the branding element in the best position to accomplish the branding operation.

5 To permit this movement, the end of the frame 18, is formed as a separate section 18a, which is pivotally connected with the main section, and adjusting screws 30, threaded through the end 10 section 18a, engage the ends of the side bars of the main section to adjust the vertical position of the section 18a, relative to the main section.

15 Pivoted on the end of the separate section 18a, so as to rock in a plane transversely of the apparatus is a support 21, which is provided with an opening into which extends an upwardly extending stem on the brander 19, a set screw 45, being threaded through the support to engage the stem. Integral with the support 21, is the 20 lug 29, extending over the end of the brander support section 18a, and having adjusting screws 28, threaded therethrough engaging said section. By adjusting the screws 28, the brander may be rocked in the transverse direction, while by adjusting the screws 30, the brander may be rocked in the longitudinal direction. By this means, the 25 branding element may be finely adjusted to ensure proper engagement with the sticks on the carrier.

30 To hold the branding element out of contact with the carrier 12, in the event that no sticks are being carried thereby, the frame 18, is provided with a cross bar 46, through which is threaded an adjusting screw 47, which is arranged to engage the support 21. The screw 47, will be adjusted so as to hold the branding element out of contact with the carrier 12, while permitting it to engage the sticks carried thereby.

35 As the stick engaging surface of the branding element is substantially flat and as the sticks are round, it is necessary to provide means for causing a rotary movement of the sticks as they pass below the branding element.

40 On the support 21, is mounted the stick rotat- 45 ing means, which, for adjustment purposes, is provided with a fixed back 31, and a face bar 32. One end of this face bar is pivoted on an eye bolt 33. Nuts 34, on this bolt provide means for adjusting the distance between the back and 50 the face bar. The other end of the face bar has an eye bolt 35, pivotally connected thereto, and the bolt is slidable through a hole in the back 31. A spring 36, mounted on this bolt 35, tends to rock the face bar away from the back, but a 55 nut 37, threaded on the bolt above the back limits this rocking movement. On the face bar are secured one or more stick engaging members having their surfaces suitably roughened to cause the sticks engaged thereby to rotate on their 60 axis as they are carried past on the carrier wheel. By adjusting the nut 31, the pressure of the stick engaging members on the sticks may be varied to ensure proper operation.

65 During the branding operation, a certain amount of moisture is exuded by the sticks, which tends to fill up the grooves 13, and prevent proper seating of the sticks in said grooves. The ribs between the grooves 13, are therefore cut away below the branding element to form a 70 shallow circumferential groove 38, on the bottom of which the sticks are supported. To keep this circumferential groove clean, I provide the scraper 39, as shown in Fig. 1 and a pad 40, carried on a bracket 41.

75 The operation of the apparatus is as follows.

A supply of sticks is placed in the hopper 2, which supply is agitated by means of the agitator 4, to ensure the proper feed of sticks to the guide 5, thence to the carrier 12. The sticks are carried by the carrier below the brander 19. 5 Simultaneously, as the sticks pass below the brander, they are caused to rotate to bring sufficient of their circumference into contact with the branding element. Further movement of the carrier 12, moves the sticks into position for 10 engagement by the stripper fingers 15, which guide the sticks into the receiving tray 17. If the branding element becomes dirty, its supporting frame 18, may be swung up and supported by the arm 22, by engaging the pin 25, in the notch 15 24, thus exposing the branding element for cleaning purposes.

What I claim as my invention is:

1. In apparatus for branding sticks and the like, the combination of a supporting frame; 20 an article carrying wheel journalled in said frame; said wheel having grooves formed transversely across its periphery to receive the articles; branding means adapted to engage articles carried by said wheel, said wheel having a 25 circumferential groove below said branding means; and scraper means for cleaning said circumferential groove as the wheel rotates.

2. In apparatus for branding sticks and the like, the combination of a supporting frame; 30 an article carrying wheel journalled in said frame; said wheel having grooves formed transversely across its periphery to receive the articles; a support pivoted at one end on said frame; and branding means carried adjacent the other end 35 of said support and adapted to engage articles carried by said wheel; a lever arm pivoted on said frame and adapted to engage said support to lift the branding means from operating position.

40 3. In apparatus for branding sticks and the like, the combination of a supporting frame; an article carrying wheel journalled in said frame; said wheel having grooves formed transversely across its periphery to receive the articles; a 45 support pivoted at one end on said frame; and branding means carried adjacent the other end of said support and adapted to engage articles carried by said wheel; a lever arm pivoted on said frame and adapted to engage said support to lift the branding means from operating position into an intermediate position; and inter-engaging means on said arm and support adapted to hold the support in an upper position.

45 4. In apparatus for branding sticks and the like, the combination of a supporting frame; an article-carrying wheel journalled in said frame; said wheel having grooves formed transversely across its periphery to receive the articles; branding means adapted to engage articles carried by said wheel; a support carried by said frame; a member movable relative to said support and resilient means for holding said member against the articles in the grooves as said articles pass the branding means; the face of 60 said member being adapted to rotate the articles in said grooves.

5. In apparatus for branding sticks and the like, the combination of a supporting frame; an article-carrying wheel journalled in said frame, 70 said wheel having grooves formed transversely across its periphery to receive the articles; branding means adapted to engage articles carried by said wheel; a support carried by said frame; a member pivotally engaged at one end 75

with said support; resilient means tending to move the other end of said member against the articles in the grooves, the face of said member being adapted to rotate the articles in said grooves as they pass the branding means.

5. In apparatus for branding sticks and the like, the combination of a supporting frame; an article carrying wheel journaled in said frame; said wheel having grooves formed transversely across its periphery to receive the articles; a

support pivoted on said frame; and branding means carried by said support and adapted to engage articles carried by said wheel; a support carried by said frame; a member movable relative to said support and resilient means for holding said member against the articles in the grooves as said articles pass the branding means; the face of said member being adapted to rotate the articles in said grooves.
